UNITED STATES PATENT OFFICE.

ISAAC H. MALLIN, OF CHICAGO, ILLINOIS.

IMPLEMENT-HOLDER FOR TYPE-WRITING MACHINES.

1,229,493.

Specification of Letters Patent. Patented June 12, 1917.

Application filed October 18, 1915. Serial No. 56,512.

To all whom it may concern:

Be it known that I, ISAAC H. MALLIN, a citizen of the United States, residing in the city of Chicago, county of Cook, and State of Illinois, have invented certain new and useful Improvements in Implement-Holders for Type-Writing Machines, of which the following is a full, clear, and exact specification.

10 This invention relates to improvements in implement holders for typewriting machines, and particularly for the disk like eraser now commonly used by operators.

15 The prime object of my invention broadly stated is to reduce to a minimum as nearly as may be the time and effort of the operator in grasping for use with, and thereafter releasing the eraser from, the fingers.

20 More specifically stated, to sustain the eraser in the most convenient location and position for seizing it for use and replacing it after use with absolute certainty, and at the same time at a point where if need be it can be instantly found and as quickly re-25 placed by sense of touch.

25 The distinguishing features of my invention lie in its novelty and general utility, and the construction, combination and arrangement of parts which find embodiment 30 therein, all as fully described with reference to the accompanying drawings and more particularly pointed out in the claims.

In the said drawings:

35 Figure 1 shows a side elevation of the attachment containing my invention in its operative position on the end bar of a typewriting machine, and a circular typewriter eraser with susceptible disks in its operative position perpendicularly adhering to the 40 magnet for grasping by the fingers of the operator.

Fig. 2 is a plan view of the same.

Fig. 3 is a cross section thereof on a line with 3-3 of Fig. 1.

45 Fig. 4 is a side elevation showing an eraser horizontally adhering to the poles of the magnet.

Fig. 5 is a view of the non-magnetic plate in blank.

50 The numeral 6 indicates the front side bar and 7 one of the end bars of the keyboard of an ordinary typewriting machine, such, for example, as the Remington machine, and 8 one of the standards thereof.

55 Secured to the end bar of the keyboard of the typewriter is a non-magnetic plate 9

preferably provided with upper and lower flanges 10 and 11 which may either be bent from the plate itself or fastened thereto, secured to which by rivets 12 and 13 is a 60 magnet 14 adhering to which in an upright position is a disk eraser 15, the flange 10 hooking over or straddling the upper edge of the end bar and held against accidental detachment by the flange 11 which clamps 65 on the under side of the end bar 7, the function of said plate interposed between the magnet and the typewriter frame being to conserve the strength of the magnet while isolating the conductivity of the typewriter 70 frame.

In the form and position of the attachment shown in Fig. 1, it will be seen and understood that the implement for which it is employed, the disk eraser shown, is in 75 such a position relative to the keyboard and the operator of the machine that the fingers in passing from the keys to the eraser have but the shortest possible distance to move when grasping it, that after grasping it with 80 the fingers it may then be moved to its operative position against the paper on the platen of the typewriter by the most direct and shortest movement of the arm, and that afterward in returning it to its original 85 position the magnet attracts the susceptible disks and holds the eraser secure from vibration, with the result that much time and effort is saved in the use of the eraser, inevitably quite frequent even with the best of 90 operators.

While I have illustrated and described the embodiment of my invention in a form designed for circular erasers equipped with steel or other susceptible disks, preferably 95 reinforced by being circumferentially raised, its use or change of form to adapt it to other articles susceptible to magnetism, and used by typewriter operators, is obvious.

It should be understood that my invention is not limited to the exact form of the plate nor to the relative position of the magnet so long as they are of such form and arrangement as will accomplish the same result.

Having fully described my invention, what I claim and desire to secure by Letters Patent is:

1. A typewriter implement holder comprising a non-magnetic plate having upper 110 and lower flanges in combination with a magnet secured thereto, said non-magnetic

plate interposed between the typewriter frame and magnet and removably attached to the side of the machine, substantially as described.

5. 2. A typewriter implement holder consisting of a magnet in combination with a flanged non-magnetic plate secured thereto interposed between the magnet and typewriter frame and removably attached to the side of the machine, substantially as described.

10. 3. A typewriter implement holder com-

prising in combination a non-magnetic plate provided with upper and lower flanges and a magnet secured thereto, said non-magnetic plate interposed between the typewriter frame and magnet and removably attached to the side of the machine for maintaining a disk eraser within convenient reach of the operator, as and for the purpose set forth. 15
